UNITED STATES PATENT OFFICE.

VOLNEY A. SEARLES, OF JACKSON, MICHIGAN, ASSIGNOR TO STEWART-WARNER SPEEDOMETER CORPORATION, OF CHICAGO, ILLINOIS, A CORPORATION OF VIRGINIA.

FUEL-FEEDING DEVICE.

Application filed September 28, 1923. Serial No. 665,490.

This invention relates to certain improvements in fuel feeding devices for use particularly in supplying liquid fuel to internal combustion engines of automobiles and the like, in connection with which it is very often desirable to have the primary fuel tank carried on the vehicle at a level below the carburetor.

The object of the invention is to provide a device of relatively simple construction and high efficiency in automatic operation, with particular relation to the construction of the vacuum tank portion thereof to which the liquid fuel is elevated as by the suction of the engine, and intermittently discharged therefrom to be fed by gravity to a vaporizing device, as for instance, the float chamber of a commercial carburetor.

The invention here claimed relates particularly to the method of operating and controlling the valves which open and close the ports of the vacuum chamber, and specifically not only to a mechanism by which all of the valves are positively and simultaneously actuated, but also to a peculiar construction of valve mechanism which controls communication between the vacuum chamber and the auxiliary chamber.

Other objects and advantages relate to the details of construction and operation, all as will more fully appear from the following description, taken in connection with the accompanying drawings, in which:

Figure 1 is a vertical cross section through the upper portion of the vacuum tank structure.

Figure 2 is a section on line 2—2, Figure 1.

The device shown is of the usual double tank construction, consisting of an upper tank —3— within which vacuum and atmospheric pressure alternate, and a lower tank —4— maintained at all times under atmospheric pressure and affording a free continuous gravity discharge of fuel to the carburetor of the engine.

The tanks may be formed of a substantially cylindrical cup-shape sheet metal structure —1— having a partition wall —2— dividing the said structure into the two chambers —3— and —4— respectively. The upper chamber —3— is connected by means of pipe —5— with a source of liquid fuel supply as the ordinary low level tank upon an automobile. This tank —3— is further

connected to a source of suction, as the manifold of the engine, by means of conduit —6— controlled by a downwardly opening valve —7—. An atmospheric inlet or vent —8— is provided for the chamber —3—, such vent being controlled by an upwardly opening valve —9— which may be positioned within the nipple —10— provided with a loose cap —11— permitting free communication with the atmosphere. Pipe —12— is provided for connecting the lower chamber —4— with the nipple —10— so as to afford at all times atmospheric communication for the said chamber —4—. The valves —7— and —9— may both be mounted upon and actuated by a single lever —13— pivoted at —14— upon the lug —15— extending downwardly from plate —16— secured to the top —17— of the upper chamber —3—. The valve —7— may, as shown, have a substantially tight pivotal connection with the lever —13— while the stem of the valve —9— is slidable through the said lever —13— and has a loose connection therewith permitting a limited relative movement of the valve stem and the lever in a manner well known. For the purpose of actuating the lever —13— to move the valves —7— and —9— to respective open and closed position, a float —35— is provided, mounted upon float stem —36— which has its upper end connected to a link —37— pivoted at —14— upon the lug —15—. The mechanism is of such character that the valves —7— and —9— are moved suddenly either to their open or their closed position and for this purpose spring —18— is provided which may be connected in any suitable manner to the link —37— and the lever —13— so that as the link moves to opposite sides of its aligning position with the lever —13— the spring —18— will snap the lever —13— either up or down, dependent upon the position of the link —18— and thereby reversely actuate the valves —7— and —9—.

As shown, the spring —18— is connected to the pivot of the link —37— with the float stem —36— and the pivot pin which connects the valve —7— to the lever —13—. In dotted lines the lower position of the float and spring and link and lever is shown while in full the upper position of those elements is illustrated. As the float rises and falls in accordance with the level of liquid within

the tank —3—, the valves —7— and —9— are operated in a predetermined desired manner.

The partition —2— is provided with an opening adapted to receive the lower threaded portion —19— of a nipple —20— having an upper substantially cylindrical portion within the chamber —3—, and formed with a perforated front wall —21—, which may be formed as an integral part of the nipple, or may be separate therefrom and secured thereto in any suitable manner, so as to form at its rear a groove, or seat, of circular form, for the reception of a rotary disk valve —22— having openings adapted to be brought into registration with and moved out of registration with the openings in the front wall —21—. These openings may be of any suitable corresponding number and of any desired shape, and as shown, are of somewhat sector shape and form, and are four in number. The valve —22— may be provided with a projecting stud —23— which extends through the front wall —21— and is formed at its outer forward portion with a disk —24—.

Between the front wall —21— and the disk —24— is mounted a link —25— in such a manner that the link freely rotates about the stud —23—. The other end of the link —25— is pivotally connected to the float stem —36—. It will be obvious that as the float stem moves up and down it will rotate the link —25— about the said stud —23—. For the purpose of effecting sudden movement of the disk valve —22— to and from a position closing the openings through the front wall —21— I have provided a spring —26— having one end connected to an eccentric point upon the disk —24— and its opposite end connected to the pivotal axis of the link —25— and the float stem —36—. As the float stem —36— moves the link —25— and carries the spring to opposite sides of the stud —23—, the spring will act to cause rotary movement of the disk —24— with respect to link —25—, thereby moving the disk valve —22— to and from a position closing the openings through the front wall —21—. As the disk valve is positioned at the rear of the front wall —21— the suction or vacuum produced in chamber —3— will hold such valve in close contact with said front wall so as to form a substantially air-tight construction.

It will be obvious from the above description that the movement of float —35— positively actuates the air valve —9—, the suction valve —7— and the discharge valve —22— so that all of said valves are suddenly and substantially simultaneously moved to the desired position, either to permit the elevation of fuel to chamber —3— by the creation of vacuum therein or to permit the free discharge of the liquid fuel therefrom

through nipple —19— when atmospheric pressure has been produced in chamber —3—. As above stated, the rotary disk valve —22— may be provided with any suitable number of openings in any desired form to correspond with the openings provided in the plate —21— so that at one position the openings in the disk valve or shutter —22— are in registration with openings in plate —21—, while in another position said openings are out of registration to form a substantial air-tight barrier between chambers —3— and —4—.

Although I have shown and described a specific construction as illustrative of a perhaps preferred embodiment of my invention, I do not desire to limit myself to the same, as various changes and modifications may be made in the details of construction, form and operation of the device without departing from the invention as set forth in the appended claims.

What I claim is:

1. In a device of the class described, a tank comprising an upper chamber and a lower chamber, means of communication between said chambers, and a rotary disk valve controlling such communication. 90
2. In a device of the class described, a tank comprising an upper chamber and a lower chamber, means of communication between said chambers, a rotary disk valve controlling said communication and float-actuated means for snapping said valve to open and closed position. 95
3. In a device of the class described, a tank comprising an upper chamber and a lower chamber, an air exhaust connection and an air inlet to the upper chamber, means of communication between said chambers, a rotary valve controlling such communication, and float-actuated means for snapping said valve to open and closed position. 100
4. In a device of the class described, comprising an upper chamber and lower chamber, means of communication between said chambers, comprising a port, and a valve mounted for sliding movement over said port in a direction transverse to the flow of liquid therethrough. 110
5. In a device of the class described, a tank comprising an upper chamber and a lower chamber, a port affording communication between said chambers with a valve seat for said port, a valve slidably movable over said seat for closing the port or opening it, and a float having a range of vertical travel in the upper chamber connected to said valve and adapted for opening and closing the port thereby in the upper and lower portions of its range respectively. 120
6. In a device of the class described, a tank comprising an upper chamber and a lower chamber, a port affording communication between said chambers with a valve seat 125

for said port, a valve slidably movable over said seat for closing the port or opening it, and a float having a range of vertical travel in the upper chamber and a yielding connection between the float and the valve adapted for opening and closing the valve in the upper and lower portions of the range of float movement respectively.

7. In a device of the class described, a tank comprising an upper chamber and a lower chamber, a port affording communication between said chambers with a valve seat for said port, and a flat valve member pivoted to swing over said seat for opening or closing the port, together with a float having a range of vertical movement in the upper chamber provided with a stem extending adjacent the valve, a guide link for said stem pivoted coaxially with the valve and yielding means movable with said link and engaging the valve arranged to be stressed at the upper and lower limits of float movement for snapping the valve to open and closed positions respectively.

8. In a device of the class described, a tank comprising an upper chamber and a lower chamber, a port affording communication between said chambers with a valve seat for said port, and a flat valve member pivoted to swing over said seat for opening or closing the port, together with a float having a range of vertical movement in the upper chamber provided with a stem extending adjacent the valve, a guide link for said stem pivoted coaxially with the valve and yielding means movable with said link and engaging the valve arranged to be stressed at the upper and lower limits of float movement for snapping the valve to open and closed positions respectively.

9. In the combination defined in claim 6, the yielding means comprising a tension spring extending from the point of connection of the link with the float stem to a point on the valve beyond its pivot, said spring being adapted to be carried past the pivot axis of the valve in the swing of the link from its upper to its lower limit.

In testimony whereof, I have hereunto set my hand at Jackson, Michigan, this 19th day of September, 1923.

V. A. SEARLES.
